DESIGN FOR A HAT

Mary Smith Downes, Tenafly, N. J.

Application February 17, 1938, Serial No. 75,207

Term of patent 7 years

To all whom it may concern:

Be it known that I, Mary Smith Downes, a citizen of the United States, residing at Tenafly, in the county of Bergen and State of New Jersey, have invented a new, original, and ornamental Design for a Hat, of which the following is a specification, reference being had to the accompanying drawing, forming a part thereof.

Fig. 1 is a perspective view of a hat, showing my new design.

Fig. 2 is a front view thereof.

Fig. 3 is a rear view thereof, on a reduced scale.

The dominant feature of my design resides in the crescent-shaped brim portion joined to the crown member, which gradually narrows from the center toward the ends, said ends having ties affixed thereto, as shown.

I claim:

The ornamental design for a hat, as shown and described.

MARY SMITH DOWNES.
